BLAST FURNACE TUYÈRE

John B. Henry, Aspinwall, Pa.

Application November 30, 1935, Serial No. 52,370

4 Claims. (Cl. 266—41)

This invention relates to improvements in blast furnace tuyères, and it is among the objects thereof, to provide a tuyère with a blast passage so formed as to gradually modify the sectional contour of the air blast stream during its passage through the tuyère forcing a definite sector of the blast stream, as it leaves the tuyère, to have a predetermined direction away from the central axis of the tuyère, maintaining at the same time 10 an unmodified velocity of blast discharge.

Another object of the invention is the formation of the blast passage in part of a tuyère by a circular wall gradually converging towards the central axis of the tuyère, joined with a diverging 15 wall, which diverging wall, with its side joining members, forms a groove in open communication with the main passage. This groove with the main passage presents at the outlet end of the tuyère, a key-hole shaped opening. The angle 20 of divergence (from the central axis of the tuyère) of the wall forming the bottom or floor of this groove, determines the discharge direction of the diverted part of the blast, and the width of the groove determines largely its cross-sectional 25 area or capacity.

Still a further object of the invention is to so proportion the capacity of the divergent groove and the angles of convergence and divergence of the blast passage walls that the total cross-sectional area of the blast passage (including groove area) at its outlet is equal to or less than the cross-sectional area at any point between inlet and outlet. This insures desired maximum discharge 30 velocity and penetration of blast, including the diverted portion.

And still a further object of the invention is to so proportion the angles of inclination of the walls of the blast passage (including the floor of divergent groove) that the inertia of the blast is 40 overcome to the extent of entirely filling the groove with air at the same pressure as the main body of blast. By experimentation, it has been found that the required maximum angle of inclination (from central axis of tuyère) is about 45 20 degrees and that best results are obtained with 10 to 15 degrees inclination.

It is understood that tuyères in service project into the burden of the furnace, being secured in a horizontal position, placed radially around the 50 circumference of the stack. The lower side of the tuyère, in this service position, is referred to as lower or bottom side.

It is generally recognized in blast furnace practice that the cause of burning the nose end of a 55 tuyère is due to unfavorable conditions of the

furnace burden, resulting in the formation of a dense area directionally below and in contact with the tuyère nose. This dense area prevents the molten metal from descending normally to the hearth and accumulates the iron in a pool, which, when it contacts the tuyère, burns the nose end and destroys its usefulness.

If, therefore, the tuyère blast passage and outlet were constructed to direct a sector of the air blast against this dense area in front of the lower 10 part of the tuyère, the oxygen bearing air would break same down through combustion, causing this part of the burden of the furnace to become porous and to move downwardly, thus preventing the formation of this dense area that frequently 15 exists with the use of tuyères having the conventional type of blast passage and discharge opening.

Patent to Holzworth #1,789,870 is directed to a blast furnace tuyère designed to apply a portion 20 of the blast downwardly a substantial distance back from the nose end of the tuyère by providing a slotted passage extending from the axial passage of the tuyère radially downward. Such structures are inefficient for the purpose intended as 25 there is no provision for forcing the desired portion of the blast through these radial slots.

In accordance with the present invention, these difficulties are overcome by effecting a progressive reduction of the cross-sectional area of the tuyère 30 passage so as to displace the desired portion of the blast into an opposing relatively long groove, the angle of inclination of which (from the central axis of the tuyère) being small enough that the inertia of the blast stream is overcome and 35 the diverted part of the blast follows definitely, upon discharge, the inclination of the floor of the groove.

In the accompanying drawing constituting a part hereof in which like reference characters 40 designate like parts:

Fig. 1 is a vertical cross-sectional view, line 1—1, Fig. 2, of an improved hollow water cooled blast furnace tuyère having a divergent groove embodying the principles of this invention; 45

Fig. 2 a front elevational view thereof;

Fig. 3 a vertical section on line 3—3, Fig. 4, of a modified form of the invention.

Fig. 4 a front elevational view of the tuyère of Fig. 3;

Fig. 5 a vertical cross-sectional view taken along the line 5—5, Fig. 6, of another modified form of tuyère embodying the principles of this invention;

Fig. 6 a front or nose end elevational view there- 55 of; and

Fig. 7 a horizontal cross-sectional view taken along the line 1—1, Fig. 6.

With reference to Figs. 1 to 2 inclusive of the drawing, the structure therein illustrated comprises a hollow tuyère 1 of frusto-conical shape, having an inner wall 2 forming a main passage 3 for the application of a blast through the nose or discharge end 4 of the tuyère. The space between walls 1 and 2 constitutes a circulating chamber for 10 a cooling medium which is applied through openings 5 and 6 in the rear, or butt end wall.

As shown in Figs. 1 and 2, a groove 7 is provided as a part of the blast passage, the groove extending a substantial distance from the approximate 15 center longitudinally of the nozzle, the grooved passage having a relatively slight inclination for the displacement through it of a definite portion of the blast. To provide for definite displacement of the blast through the groove 7, the inner wall 2 of the tuyère is of gradually reducing diameter 20 to provide a progressively reducing cross-sectional area for the passage of the blast, it being desirable that the combined areas of the nose end and groove are no greater than the area at "x—x", at 25 which point the modification of the sectional area of the blast stream starts.

In the hereinbefore mentioned prior art structures, the slot at the discharge end of the tuyère was ineffective to direct the blast as it was non-30 confining and was not so proportioned with the tuyère passage to cause displacement of a portion of the blast therethrough.

In the design shown in Figs. 1 and 2, the total area of the main blast passage 3 and the groove 7 at the discharge end is preferably less but no 35 greater than the area of the blast passage at any other point in the tuyère, with the result that there is no expansion of the blast stream (with attending loss of velocity).

40 The modified form of slot 1a shown in Figs. 3 and 4 is desirable when the outside diameter of the nose end of the tuyère is unusually small. In Fig. 3 the groove 1a extends downwardly below the nose end of the tuyère as in the structure disclosed in the patent to Holzworth. The structure of Fig. 3 herein differs from that of the prior art in that the entire blast passage is progressively constricted so that section area at "y—y" is equal to or less than the area at any other point in the 50 passage, thus forcing a definite displacement through groove 1a.

The form of blast passage shown in Figs. 5 to 7 inclusive of the drawing may be required in some applications. When it is considered that the blast 55 inlet diameter is fixed while the desired discharge area varies greatly, the advantage of this form of construction is obvious for small capacity tuyères, so that the proper angle of divergence of the bottom of the groove may be secured.

60 As shown in Fig. 6, the groove 10 is of greater width than the groove 7 in Fig. 2, and the groove of Fig. 2 is of greater depth than groove 10 of Fig. 5.

Thus it is seen that modifications may be made 65 in the shape of the tuyère passage as well as in the width and depth of the divergent groove to carry out the same principle, i. e., the displacement of a portion of the blast into the divergent groove area to discharge oxygen-laden air to the furnace burden directly adjacent the tuyère and in line 70

with the groove to prevent the accumulation of molten metal and the burning-out of the tuyère as is common with the conventional form of tuyère construction.

The inclination of the divergent groove may 5 vary within certain limits in accordance with the degree of convergence of the main blast passage, but the angle of inclination of the divergent groove from the axis of the tuyère should be substantially oblique and materially less than 45°, as it would 10 be impossible or impractical to divert the desired portion of the blast through an angle of substantial degree, on account of the inertia of the high velocity blast used in the art.

Although several embodiments of the invention 15 have been herein illustrated and described, it will be apparent to those skilled in the art that various modifications may be made in the details of construction without departing from the principles 20 herein set forth.

I claim:

1. A blast furnace tuyère comprising a body having a main passage of gradually reducing cross-section toward the nose of the tuyère for the transmission of air and a joining divergent 25 groove communicating with said main passage progressively reducing in cross-sectional area from the nose of the tuyère to the rear thereof so that the combined area of the main passage and divergent groove will be no greater at the 30 outlet end of the passage than at any point between inlet and outlet.

2. A blast furnace tuyère comprising a body having a main air passage therein of gradually reducing cross-section toward the nose of the tuyère and having a divergent auxiliary passage communicating with the main air passage from substantially the center of the length of said air passage to the nose end of the tuyère, said auxiliary passage, through its entire length, being 40 in open communication with the main air passage and of progressively increasing cross-sectional area toward the nose of the tuyère while the main air passage is of progressively decreasing cross-sectional area. 45

3. A water-cooled blast furnace tuyère comprising a hollow body having a main air passage of constant or progressively decreasing cross-sectional area from the air inlet to the outlet thereof, a divergent passage in open communication with said main air passage and of progressively increasing cross-sectional area toward the nose of the tuyère for directing a sector of the blast in an oblique outwardly direction. 50

4. A water-cooled blast furnace tuyère comprising a hollow body having a main air passage of constant or progressively decreasing cross-sectional area from the air inlet to the outlet thereof, a divergent passage in open communication with said main air passage and of progressively increasing cross-sectional area toward the nose of the tuyère for directing a sector of the blast in an oblique outward direction, the inclination and width of said divergent passage 60 being such that the combined main air passage and the divergent passage area is progressively reducing in the direction of the air inlet to the air outlet of the passage. 65

JOHN B. HENRY.
